UNITED STATES PATENT OFFICE.

RICHARD WALTER GREGORY, OF NEWCASTLE-ON-TYNE, ENGLAND, ASSIGNOR TO
ELECTRICAL IMPROVEMENTS LIMITED, OF NEWCASTLE-ON-TYNE, ENGLAND.

OIL-BREAK ELECTRIC SWITCH.

1,366,791.

Specification of Letters Patent. Patented Jan. 25, 1921.

Application filed November 3, 1917. Serial No. 200,141.

To all whom it may concern:

Be it known that I, RICHARD WALTER GREGORY, a subject of the King of England, and residing at Newcastle-on-Tyne, in England, have invented certain new and useful Improvements in Oil-Break Electric Switches, of which the following is a specification.

This invention relates to improvements in oil-break electric switches and its object is to quench the arc produced as quickly and efficiently as possible by rapid removal of the hot conducting vapors from between the contacts, replacing them by means of cool oil, so arranging that these vapors shall not come in contact with conductors of different potential within or close to the switching mechanism, so elongating and attenuating the arc that its exposed surface shall be as large as possible with respect to its volume, utilizing the buoyancy of the hot vapor constituting the arc for this purpose, setting up a natural circulation of the oil so as to bring cool parts thereof to the arc, and producing all these effects by the natural forces set up by the electric current broken at the switch.

This is accomplished according to this invention by so arranging the contact arms that the arc produced between them is substantially horizontal, by providing a free vertical vent for the vapors and by so disposing the conductors through which the current passes to the contact arms that the electromagnetic forces tend to elongate the arc and force it upward through the oil.

Further, a tubular screen formed of or lined with insulating material is arranged to surround the contact arms to shield the conductors from contact with the products of the arc and to assist in the circulation of the oil caused by the arc vapors.

In the accompanying drawings which illustrate diagrammatically three typical forms of oil-break switch according to this invention,

Figure 1 is a vertical section showing the contact arms open.

Fig. 2 a similar vertical section showing the contact arms in their normal or closed position, and

Fig. 3 a plan section of a construction of the improved switch in which the contact arms and the conductors entering and leaving the switch are in the same vertical plane.

Fig. 4 is a figure showing the circulation of the cooling oil.

Fig. 5 is a view corresponding to Fig. 1, but of a form of switch in which the contact arms and the conductors entering and leaving the switch are arranged in vertical planes at right angles to one another.

Fig. 6 is a vertical section at right angles to Fig. 5.

Fig. 7 is a sectional plan.

Fig. 8 is a vertical section of a construction embodying modifications of the screen and tank and of the contact arms.

Fig. 9 is a plan of the form of screen shown in Fig. 8 and of the contact arms, 70 and

Fig. 10 shows, by way of example only, one construction of mechanism for opening and closing the contact arms.

With reference first to the construction 75 represented in Figs. 1, 2 and 3, A is the oil tank containing oil up to say the level of the broken line B, and C is a vent of ample size leading to the atmosphere or if desired out of the building in which the 80 tank is situated. D, D' and E, E' are respectively the conductors by which current enters and leaves the switch. These conductors pass through the tank cover A' by the insulating bushings F, F' proceeding 85 vertically through the oil and bending horizontally at the points d, e toward the points d', e'. Here they join the hinged or pivoted contact arms G, G'. The circuit is broken by the parting of these arms which may be 90 caused by any convenient mechanism such for example as is hereinafter described with reference to Fig. 10. The arc produced on the breaking of the circuit has normally 95 (when considered as uninfluenced by the repelling forces hereinafter referred to) a substantially horizontal path between the ends of the arms G, G' as shown by the dotted line f. Between the vertical conductors D, E and the contact arms G, G' and of 100 such dimensions as to enable the said arms to move fully apart, an annular or tubular screen H of insulating material is arranged so as to be entirely immersed in the oil. The main object of this screen is to prevent the 105 arc products from coming into contact with the conductors D, E.

It will be seen that in the arrangement shown the buoyancy of the hot vapors produced by the arc causes them to rise upward 110

through the oil so lengthening and increasing their cooling surface. This tendency is of use in assisting to break the circuit. It will also be seen that the direction of current in the horizontal portions D' and E' of the entering and leaving conductors is opposite to that of the current in the arc. An electromagnetic force is therefore produced which elongates the arc by repelling it upward as shown by the bow-shaped line f'. When the arc is thus bow-shaped the direction of the current in the bowed ends of the arc is the same as is the direction of the current in the adjacent vertical conductors D, E so that these bowed ends are attracted toward the said vertical conductors and the arc thus still further elongated, see line f². These repelling and attracting forces together with the buoyancy of the arc products produce a great attenuation of the arc so that it is more readily cooled by the oil than would otherwise be the case. These repelling and attracting forces being proportional to the current passing through the circuit are most beneficial when most required, that is to say, when the switch is breaking heavy currents as for instance may occur when there is a breakdown of apparatus supplied by the circuit.

It is to be noted that the screen H entirely surrounds the arc and that it is placed well above the bottom of the tank A and below the surface of the oil therein. A free circulation of the oil is therefore able to take place as shown by the arrows in Fig. 4. When an arc is formed, the hot arc vapors rise rapidly to the surface of the oil. Such portion of the oil as is heated by the arc passes upward within the screen and is replaced by cool oil from the lower parts of the tank.

The form shown in Figs. 5, 6 and 7 differs from that already described in that the conductors D, E instead of being in the same vertical plane as the contact arms G, G' are in a vertical plane at right angles thereto. In this form the arc is still repelled upward by the current in the horizontal portions D', E' of the conductors as is shown by the bow-shaped broken lines f', f² in Fig. 5. At the same time the attracting forces of the current in the vertical portions D, E of the conductors attract the bowed ends of the arc so as to give the latter a form which in plan resembles the letter S. This is clearly shown by the curve f³ in Fig. 7.

In Figs. 8 and 9 it will be seen that the screen H differs from that shown in the figures already described. Instead of being merely a hollow cylinder of insulating material it consists of such a cylinder acting as a liner to a hollow cylinder of metal H', a much stronger construction and one more capable of withstanding severe explosions being thus obtained. It will also be seen

that in this case the vent C instead of springing from the tank cover or switch top A' is an upward prolongation of the metal part H' of the screen. As shown in Fig. 8 the insulating liner H extends somewhat below the lower part of the metal cylinder H' so as the better to protect the conductors connected with the contact arms from the effects of the arc. In the construction here illustrated the holes H² serve to permit circulation of the oil as before.

Figs. 8 and 9 also illustrate an arrangement in which the contact arms G, G' are crossed. This obviates the crossing or overlapping of the horizontal parts D', E', of the conductors connected with them. In this case the arms are made with lateral extensions G², G³ at their heads or free ends so as to shut or lock against one another. The contact arms may be insulated except at the contacting parts.

In Figs. 1 to 9 which are merely diagrammatic no mechanism is shown for opening and closing the contact arms G, G' but it is to be understood that any suitable arrangement may be employed.

By way of example only Fig. 10 shows a mechanism which may be used for the purpose. The contact arms G, G' are mounted upon insulating or insulated shafts J, J' and at each end these shafts are provided with jointed levers K, K' the lower ends of the levers K' being pivoted or hinged to a block L' mounted on a shaft L. This shaft L can be moved up and down by any mechanism such as is commonly used in oil-break electric switches and its motion causes the opening and closing of the contact arms G, G'.

It is to be understood that the contact arms G, G' need not necessarily be the only contacts of the switch; in switches for large loads other contacts may be used in conjunction with them such contacts being arranged to close after and open before the contact arms G, G' which then act as arcing or sparking contacts.

What I claim as my invention and desire to secure by Letters Patent is:—

1. In an oil break electric switch the combination with a tank adapted to contain insulating liquid, of a switch immersed in the liquid, a plurality of conductors entering the tank above the level of the switch and connected to the switch contacts and a single insulating member interposed between the switch and conductors in such manner as to completely protect the conductors from the vapors resulting from an arc formed at the switch.

2. In an oil break electric switch the combination with a tank adapted to contain insulating liquid, of a switch immersed in the liquid, conductors entering the tank from above the switch and connected to the contacts of said switch, and an insulating mem-

ber in said tank interposed between the switch and conductors, said member extending below the switch and being disposed to protect the conductors from the vapors resulting from an arc formed at the switch.

3. An oil break electric switch comprising in combination, a tank adapted to contain insulating liquid, said tank having a cover provided with a vent, movable electric switch contacts within said tank disposed below said vent whereby an unobstructed path is afforded for the vapors rising from the arc, and conductors entering the tank above the level of the insulating liquid extending to a point below the point of formation of the arc and connected to said contacts, each conductor within the tank having a portion extending parallel to the arc whereby the electro-magnetic force therein tends to elongate the arc and force it upward through the liquid.

4. An oil break electric switch comprising in combination, a tank adapted to contain insulating liquid, said tank having a cover provided with a vent, contacts in said tank located beneath said vent and positioned to form a horizontal arc when separated, conductors entering the tank above the level of the liquid and leading the current to and from the contacts, and a tubular insulating screen within the tank, surrounding the contacts and serving to shield the conductors from the products of the arc.

5. In an oil-break electric switch the combination of a tank adapted to contain insulating liquid, contacts within said tank so disposed that the arc formed between them when circuit is broken is substantially horizontal, conductors leading the current to and from the contacts, and a tubular insulating screen within the tank and serving to shield the conductors from the products of the arc, said screen being so disposed

as to cause the vapors of the arc to set up 45 a circulation in the insulating liquid in the tank.

6. In an oil-break electric switch the combination of a tank adapted to contain insulating liquid, contacts within said tank 50 so disposed that the arc formed between them when circuit is broken is substantially horizontal, conductors leading the current to and from the contacts, a tubular insulating screen within the tank and serving to shield 55 the conductors from the products of the arc and a free vertical vent for the vapors through the upper part of the tank above the contacts said vent forming a continuation of the tubular screen.

7. In an oil-break electric switch the combination of a tank adapted to contain insulating liquid, contacts within said tank so disposed that the arc formed between them when circuit is broken is substantially horizontal, conductors leading the current to and from the contact said conductors being so disposed relatively to the contacts and to the line of the arc formed between them when circuit is broken that the electromagnetic forces tend to elongate the arc and force it upward through the oil, a tubular insulating screen within the tank and serving to shield the conductors from the products of the arc, said screen being so disposed 75 as to cause the vapors of the arc to set up a circulation in the insulating liquid in the tank, and a free vertical vent for the vapors through the upper part of the tank above said tubular screen and means for 80 opening and closing the contacts.

In testimony whereof I have signed my name to this specification in the presence of two subscribing witnesses.

RICHARD WALTER GREGORY.
